RADIATOR AIR VALVE

Wainwright Tuttle, Madison, N. J., assignor to
 Bridgeport Brass Company, Bridgeport, Conn.,
 a corporation of Connecticut

Application July 25, 1941, Serial No. 403,941

13 Claims. (Cl. 236—63)

The present invention relates to air valves and more particularly to air valves used in conjunction with radiators employed in heating systems.

One of the principal objects of this invention is the provision of novel means for preventing water which may be present in the valve while it is venting from reaching the exit orifice and escaping from the valve.

Another object of the invention is to provide effective silencing means whereby quiet venting of the valve results.

Still another object is to provide novel "spread band" venting adjustment means which will permit geometric rather than arithmetic control of the venting rate whereby there is a better spread of desirable adjustability over the control range, achieving thus a venting control analogous to "spread band" tuning control in radio.

A further object is the provision of novel adapter means to facilitate use of the air valve with either side, or top venting orifice provided radiators.

Another object is the provision of an air valve which may be manufactured cheaply and simply assembled, and which comprises a minimum number of working parts.

To the accomplishment of the foregoing and such other objects as may hereinafter appear, this invention consists in the novel construction and arrangement of parts hereinafter described and then sought to be defined in the appended claims, reference being had to the accompanying drawings forming part hereof and which show, merely for the purposes of illustrative disclosure, preferred embodiments of the invention, it being expressly understood, however, that various changes may be made in practice within the scope of the claims without digressing from the inventive idea.

In the drawings, in which similar reference characters denote corresponding parts,

Fig. 1 is a perspective view of the radiator valve applied directly to a radiator;

Fig. 2 is a similar view of the valve applied to a radiator of the type having a vertical tapping for the air valve on top, through the agency of a novel form of adapter;

Fig. 3 is a vertical section of the air valve construction taken along line 3—3 of Fig. 1 and viewed in the direction of the arrows;

Fig. 4 is a vertical section taken along line 4—4 of Fig. 3, also viewed in the direction of the arrows;

Fig. 5 is a transverse section taken along line

5—5 of Fig. 3, also viewed in the direction of the arrows;

Fig. 6 is a transverse section taken along line 6—6 of Fig. 3, also viewed in the direction of the arrows; and

Fig. 7 is a partial vertical section taken along line 7—7 of Fig. 2, illustrating details of construction of the adapter.

Referring now to the drawings 10 denotes a hollow air valve casing or shell. This shell is especially shaped so as to be greater in breadth than in height or depth. The rear wall 11 is substantially flat, the adjacent side walls 12 and 13 are curved outwardly therefrom and the front wall 14, which joins the two side walls 12 and 13, is further outwardly curved to a shape corresponding substantially to a portion of a cylinder of revolution. The two curved side walls 12 and 13 define what may be termed wing or extension chambers 16 and 17, which extend at opposite sides from the central float chamber 18 defined by the front wall 14 and rear wall 11. These wing chambers have a purpose to be hereinafter described.

25 A bottom member 20 is suitably attached at 21 in sealing relationship to the shell, as by beading and soldering. This bottom is provided with a threaded opening 22 into which a float-positioning member, or screw 23 is screwed for a purpose to be presently described.

20 The top 24 of the casing 10, which, in the embodiment shown, is integral with its side walls 11, 12, 13 and 14, and substantially flat, is provided with a single opening 30 in which a valve seat body 31, to be presently described, is mounted. An annular ridge 32, concentric with the opening 30, is provided in the top 24 for a purpose to be presently described.

25 The rear wall 11 has an opening 33 whose edge is offset, defining a flange 34. A suitable threaded spud 35 is provided. This spud has a supporting flange 36 which may be annular, engaging flange 34 and suitably attached thereto, as by soldering or the like. The passageway 37 in the spud serves as an air and steam inlet to and as a water outlet from the chamber 18 in well-known manner. The threaded portion 38 of the spud facilitates quick attachment of the device to a radiator or other part, as will be hereinafter described.

30 A hollow receptacle 40 rests on the inner end of the positioning screw 23. This receptacle acts as a float and also contains an expandible fluid 41 which, when steam or hot water enters the chamber 18, becomes heated and expands, and

forces the bottom 42 of the float outwardly so as to raise the float and cause the valve member 43 therein to engage a seat 44 in the valve seat body 31 and to close the escape passageway or orifice 45 in the valve body 31. The height of the float 40 is so admeasured as to provide a comparatively large amount of space between its top and the top 24 of the casing.

The valve seat body 31 comprises a substantially cylindrical body of suitable material such as brass or other metal which is provided on its bottom with a downwardly extending skirt or flange 46 which terminates in a sharp dripping edge 47. The dripping edge is at a comparatively large distance from the orifice 45. The body 31 is shoudered at 48 and the reduced portion 49 adjacent the shoulder fits into and extends through the opening 30 to the upper side of the casing top, being suitably attached in place as by soldering, at 50, or the like. The body is further reduced in diameter and tapered at 51 and provided with a flat top seating surface 52 into which the escape passageway or orifice 45 opens. A threaded stud 53 integral with the body 31 extends upwardly of the surface 52. This stud serves for the attachment of venting control and silencing parts to be presently described.

A combination drip, air and float guide 60 is provided in the chamber 18. This guide is so designed as to direct the air entering the chamber from the radiator upwardly substantially parallel to and alongside the rear wall 11 to a point above the usual liquid level L in the chamber 18 and then laterally in two opposite streams toward the walls 12 and 13 of the wing chambers 16 and 17 at points remote from the escape passageway 45 so that the escape path for air and entrained droplets of moisture blown into the casing 10 is increased to an extent which, to all practical purposes, eliminates the blowing of droplets through 40 the escape passageway 45 by the gravity separation of the droplets from the air in its passage through the casing. This direction of the air also has the effect of making the horizontal component of air velocity substantially larger than its vertical component so that droplets of entrained water can fall more freely under gravity actuation without reaching the orifice 45. The lateral direction of the air blows it into contact with the walls 11 and 12 before it reaches the outlet passageway 45, and, as a result, the air must turn sharply, providing additional inertia or centrifugal separation effect for the moisture or droplet content.

To effect these results, the air guide consists of a partitioning wall 61 extending substantially parallel to the wall 11 of the casing and spaced therefrom by the bent over top flange 62 and bent over side flanges 63, 64. The side flanges 63, 64 are suitably attached, as by welding or soldering or the like at 65 to the wall 11, and with the latter and wall 61 define a vertical air passage 66. Each of the side flanges 63, 64 terminates short of the top flange 62, and above the usual water level L in the casing defining oppositely located lateral openings 67 for the air passageway 66 above said water level. The wall 61 has two oppositely extending guide flanges 69, in the region of the openings 67 to aid in guiding the air emerging from the openings 67 toward and into the wing chambers 16 and 17. These flanges 69 extend substantially 70 parallel to the casing wall 11 and are spaced therefrom.

Integral with vertical wall 61 are a pair of horizontally extending float guide flanges 70, 71 which are provided with curved guiding edges 12, 13 75

which receive the float 40 and guide its vertical movement.

Also integral with the wall 61, and extending horizontally therefrom into the spud passageway 37, is a drip guide flange 74. This flange has a width slightly less than the diameter of the spud passageway 37 and divides the latter into two separate compartments. The upper (air) compartment is larger than the lower (water) compartment. This reduces resistance to air in flow. At the same time water can flow out more readily. The outer end 75 of the drip flange 74 is bent upon itself into channel form to facilitate return flow of water from the chamber 18.

15 A suitable guide abutment 80 is provided at the front wall 14. This abutment, together with the curved edges 72, 73 of the guide flanges 70 and 71 serves to center the float 40 with respect to outlet passageway 45, and to guide its movement vertically, preventing disarrangement of the valve pin 43 with respect to the seat 44 in valve body 31. If desired the reentrant ribs 81 on the wall 14 can extend far enough into the casing to serve as guides in place of and for the same purpose as 20 abutment 80.

25 Venting of air through the passageway is to be at a controlled rate. The venting rate of this device herein is adapted to be a geometric, rather than arithmetic, progression whereby a control analogous to "spread band tuning in radio" is effected. Also, silencing means in conjunction with the control means are provided whereby quiet, as well as controlled, venting is effected. To accomplish this, a modulator 85 is provided.

30 This modulator in the embodiment shown comprises an inverted cup-shaped shell 86. This shell has a reentrant centrally located portion 87 in its end wall 88 which is substantially cylindrical in shape and provided with a bottom 89. The latter is adapted to seat on the surface 52 of the valve body 31 and is centered with respect thereto on the stud 53 which projects through a centrally located opening 90 in the said bottom 89.

35 The bottom 89 is provided with a groove 91 concentrically arranged with respect to the opening 90 and so located as to overlie the venting orifice 45. This groove varies in depth and width progressively increasing as to both from its end 92 to its junction 93 with an arcuate open slot 94 whose width increases progressively from the junction 93 to its end 95, the width of the slot and groove at their junction 93 being respectively of widths which provide continuous and smooth increase in venting rate so that the slot 94 in effect constitutes an uncovered continuation of the groove 91. The narrowest portion of the groove 91 at its end 97 is considerably less in width than the diameter of the exit orifice 45 in the valve body, while the widest portion of the slot 94 at 95 is substantially equal in diameter to that of the exit orifice 45. The rate of change of dimensions of the groove and slot are such as to provide a geometric venting control rate.

40 The ends 92 and 95 are separated by the portion 98 of the bottom 89. This portion is so admeasured that it can never completely close the orifice 45 when overlying the latter.

A plurality of suitably arranged perforations 99 are provided in the bottom 89. These perforations are so positioned as to overlie the tapered portion 54 of the valve body (Fig. 3) for a purpose to be presently described.

45 The outer skirt 90 of the modulator member 86 is so admeasured in height and diameter that its bottom edge 99 rests on the top surface of

the casing top 24, except for a small portion at the rear wall 11 of the casing which overhangs the latter to provide a clearance passage 100 (Fig. 3) for escape of air, as will be presently described. The top surface of the casing is roughened so that the bottom edge of the modulator does not lie in sealing engagement with it. The chamber 101, defined by the modulator and top wall 24, serves as a silencing chamber, as will be presently described.

A locking member 102, admeasured to fit within the reentrant portion 87 of the modulator, threadedly engages the stud 53, serving, when screwed down tightly, to clamp the modulator in any adjusted position. This member 102 has an annular groove 103 in its bottom which overlies the perforations 98, the groove 91, and slot 94, serving as an air conduit and first sound deadening chamber. This groove causes air which emerges from the orifice 45 to spread around in groove 103 and escape as shown by the arrows into chamber 101 through the perforations 98 which offer large resistance to the sound wave created by the air emerging from orifice 45, but little resistance to air flow. This prevents most of the noise of impingement of the original air jet from orifice 45 from reaching the chamber 101. Escaping air in the latter is much quieter, but still audible. This, in turn, is reflected by the ridge 32 into and is quieted by the comparatively large chamber 101, in which the sound waves expand. The final escape of air into the room occurs all around, between the skirt edge 99' and the top surface of the casing 10, and largely through the clearance 100. The result is efficient silencing of venting from the radiator.

The modulator skirt 99 externally is provided with indicator marks to denote different degrees of venting. In the embodiment these constitute the Roman numerals I, II, III, IV—X. A suitable reference indicator 105 is provided on the casing to indicate with these numerals the relative position of the modulator groove 91 and slot 94 with respect to the orifice 45.

The dimensioning of groove 91 and slot 94 are such that flow of air at, say $\frac{1}{2}$ lb. per square inch pressure, through the valve orifice can range from $\frac{1}{5}$ to 15 cubic feet per hour. When the modulator is rotated the change of groove and/or slot dimensions over the orifice 45 from numerals I to X is such that the flow increases about 60% (actually 61.7% in one embodiment) per step. That is, numeral I, opposite indicator 105, represents the lowest rate of flow. With numeral II opposite indicator 105, the slot and groove have been rotated so that venting is about 60% higher in cubic feet per hour than at I, and at II, about 60% higher than at II, et cetera. This provides "spread band" adjustment of the venting rate. The geometric, rather than arithmetic, progression of venting rate provides a control analogous to "spread band tuning" in radio.

The spud 35 is normally screwed directly into the usual side opening (not shown) of a radiator R and the valve is ready for use.

The valve, however, may also be used with convector type radiators R' which usually have a vertical tapping T for the air valve on top. In such cases, since the air valve will not operate properly if the float is other than vertical, an adapter becomes necessary. However, since the overall height of the air valve is comparatively small, the casing 10 has a small swing about its spud 35, and, as a result, the adapter can also be short.

In the embodiment shown, the adapter 110, comprises a body of suitable material, such as cast iron, or the like. This body has threaded spud 111 at one end dimensioned to fit the threaded portion T' of the radiator opening T. The body flares outwardly from the threaded portion at 112 and terminates in a head 113 which extends transversely at 114. The body is provided with a longitudinal bore 115 which terminates at its inner end in an enlarged chamber 116 in the head 113. A transversely extending threaded bore 117 in the head 113 also communicates with the chamber 116 so that a complete passageway through the body with a right-angle bend therein is provided. The spud 35 is adapted to threadedly engage in the bore 117. The adapter 110, when attached for the opening T' in effect, provides a horizontal outlet 117 for the radiator into which the threaded spud 35 can be screwed.

A split-drip or siphon tube 120, carried in the bore 115, provides positive drain back. The tube has a split, or slot 121, extending its full length. With the split tube, the siphon effect is not lost, yet water can enter it at any point. A plain tube, even with a hole drilled in it, just above the point where it projects from the bottom, will "hang up" (remain water bound). The split tube eliminates this difficulty. At its inner end the tube 120 is provided with wings 122 which engage the shoulder 123 defined at the entrance of bore 115 into chamber 116. These wings are sufficiently deformable and compressible because of the split 121 to permit the tube to be assembled with the adapter by pushing it through the bore 115 from the end 111, until the wings clear the bore 115 and spread in chamber 116 to engage the shoulder 123.

The height of the tapered portion 112 of the adapter body is just sufficient to permit clearance above the radiator for rotation of the valve casing 10 with spud 35 as a center during its attachment in the adapter opening 117. This height is comparatively short because of the small height of the valve casing 10.

In operation of the air valve, air from the radiator enters the spud 35 primarily in the upper compartment above the partition 74, and is directed upwardly in the passageway 66 by the wall 61, passing outwardly therefrom in dual oppositely moving streams above the liquid level in the casing 10 through the openings 67. In its movement the air carries with it droplets of moisture from the radiator. The main velocity components of the air and droplets as its streams emerge from the openings 67, are horizontal, while the vertical components of velocity are comparatively small. The horizontal components drive the air with entrained droplets, in the dual oppositely directed streams into the wings 16, 17 against the walls 12 and 13, causing air to turn sharply creating a whirling action and consequent longer path for the air before it reaches the exit orifice 45. In this lengthened path gravity action on the droplets is greater than the small vertical air velocity components and permits substantially complete and fast elimination by gravity of the moisture droplets in the air, so that substantially none of them reaches the exit orifice 45. Moreover, the two wings of the body shape and the form of the air director furnish two points of discharge for the bubbles, inevitably formed by the passage of air through the draining water content of the casing 10, into the separation space above the water level and into the wings 16 and 17 at a considerable distance from the exit orifice 45. This

allows space for the bubbles to expand and burst before the membranes of water can reach the exit orifice 45.

Moreover, the sharp annular skirt 47 on the valve body 31 is located at some distance from the exit orifice 45 thereof, and projects below the inner face of top wall 24. This prevents moisture condensed or splashed on the top inner surface of the body from reaching the exit orifice. Such drops will drip off the sharp skirt end 47 since the velocity of flow of air toward the orifice 45 at the distance of the skirt 46, and on its comparatively large circumference, is not rapid enough to entrain and carry the drops to the orifice.

The moisture-free air passes out through orifice 45 moves around groove 91 to the slot 94, thence around groove 103, and through perforations 98 into chamber 101, whence it, with the residual sound wave, is reflected by the annular ridge 32 against the wall of the skirt before it passes silently to atmosphere, as has been described above.

When steam or hot water enters the valve, the float rises and simultaneously its diaphragm 42 expands to seat valve body 43 on its seat 44 to shut off the valve orifice and thus prevent escape of steam or hot water through the said orifice. The adjustment screw 23 serves to regulate the cut-off temperature for the valve by regulating the open position of the float. It is usually set by the manufacturer, and fastened against tampering at 23' by solder or the like.

Excess water in the valve at any time drains in well-known manner through the lower compartment in the spud 35, being assisted by the channelled siphon wings 15 on the end of member 74.

If the adapter is used, the split siphon tube 120 facilitates drainage in the adapter to the radiator R'.

For ready reference, a recess or depression 130 in simulation of the venting control groove 91 and slot 94 can be provided on the top face 88 of the modulator 86 to give a further visual indication of the relative venting control rate. This groove 130 may be visually set off from the balance of the modulator by giving it coloring different from that of the balance of the modulator.

While specific embodiments of the invention have been described, it is to be understood that variations within the scope of the appended claims are contemplated. There is no intention of limitation to the exact details shown and described.

I claim:

1. In a device of the character described, a casing having a pair of opposed faces defining a float chamber and joining faces connecting said two opposed faces, said joining faces defining a pair of wing chambers each adjacent said float chamber and opposite each other and each being in free communication with said float chamber, one of said opposed faces having an inlet in its lower region leading to said float chamber, and a guide member within said float chamber opposite said inlet and provided with a substantially vertical passageway opening into two oppositely directed passageways above the normal liquid level in said device for guiding air and entrained droplets of moisture discharged into said inlet from a radiator first upwardly above the said normal liquid level and then in oppositely directed streams toward and into said wing chambers and from there into said float chamber, said float chamber having an outlet in its top for the venting of air through it so that the

horizontal component of air velocity above the normal liquid level in said device exceeds that of the vertical component thereof in a portion at least of the path of travel of the air within said chambers to said outlet and the entrained droplets of moisture may separate from said air by gravity.

2. In a device of the character described, a casing having a pair of opposed faces defining a float chamber and joining curved faces connecting said pair of opposed faces and defining oppositely located auxiliary wing chambers each of which is in open communication with said float chamber, one of said opposed faces having an air inlet adjacent its bottom leading to the float chamber, a guide member arranged within said float chamber opposite said inlet and provided with a substantially vertical passageway opening into oppositely directed horizontal passageways above the normal liquid level in said device for guiding air and entrained droplets of moisture entering said inlet first to above the said normal liquid level and then laterally in oppositely directed streams into said wing chambers and from there by the shape of said curved joining faces with a whirling motion into said float chamber, said float chamber having an air outlet in its top for the venting of air from it whereby the air passing through said chambers has larger horizontal than vertical components of velocity in portions of its paths at least to facilitate gravity separation of entrained drops of moisture from the air prior to its said venting and to facilitate breaking in said casing of the water film of bubbles formed by passage of air through water in said casing.

3. In a device of the character described, a casing having a pair of opposed faces defining a float chamber and joining curved faces connecting said pair of opposed faces and defining oppositely located auxiliary wing chambers each of which is in open communication with said float chamber, one of said opposed faces having an air inlet adjacent its bottom leading to the float chamber, a guide member arranged within said float chamber opposite said inlet and provided with a substantially vertical passageway opening into oppositely directed horizontal passageways above the normal liquid level in said device for guiding air and entrained droplets of moisture entering said inlet first to above the said normal liquid level and then laterally in oppositely directed streams into said wing chambers and from there by the shape of said curved joining faces with a whirling motion into said float chamber, said float chamber having an air outlet in its top for the venting of air from it whereby the air passing through said chambers has larger horizontal than vertical components of velocity in portions of its paths at least to facilitate gravity separation of entrained drops of moisture from the air prior to its said venting, and means for controlling the rate of venting through said air outlet.

4. In a device of the character described, a casing having a pair of opposed faces defining a float chamber and joining curved faces connecting said pair of opposed faces and defining oppositely located auxiliary wing chambers each of which is in open communication with said float chamber, one of said opposed faces having an air inlet adjacent its bottom leading to the float chamber, a guide member arranged within said float chamber opposite said inlet and provided with a substantially vertical passageway

opening into oppositely directed horizontal passageways above the normal liquid level in said device for guiding air and entrained droplets of moisture entering said inlet first to above the said normal liquid level and then laterally in oppositely directed streams into said wing chambers and from there by the shape of said curved joining faces with a whirling motion into said float chamber, said float chamber having an air outlet in its top for the venting of air from it whereby the air passing through said chambers has larger horizontal than vertical components of velocity in portions of its paths at least to facilitate gravity separation of entrained drops of moisture from the air prior to its said venting, means in said float chamber responsive to the presence therein of heated fluid to close off said air outlet, and means for controlling the venting of air through said air outlet at a geometric rate.

5. In a device of the character described, a casing having a pair of opposed faces defining a float chamber and joining curved faces connecting said pair of opposed faces and defining oppositely located auxiliary wing chambers arranged laterally thereof, each of which is in open communication with said float chamber, one of said opposed faces having an air inlet adjacent its bottom leading to said float chamber, a guide member arranged within said float chamber opposite said inlet and provided with a substantially vertical passageway opening into two oppositely directed horizontal passageways above the normal liquid level in said device for guiding air and entrained droplets of moisture entering said inlet first vertically to above the said normal liquid level and then laterally in oppositely directed separate streams, one toward each wing chamber, and from there by the shape of said curved joining faces with a whirling motion into said float chamber, said float chamber having an air outlet for the venting of air through it whereby the air passing through said chambers has larger horizontal than vertical components of velocity to facilitate gravity separation of entrained drops of moisture from the air prior to its said venting, means for silencing the air venting through said air outlet, and means for controlling said venting air at a geometric rate.

6. In a device of the character described, a casing having an inlet, means to permit discharge of air from said casing, said means comprising a body supported by said casing and having an outlet orifice provided with a valve seat at its inner end, and a top seating surface at its opposite end, a temperature controlled valve adapted to cooperate with said seat, and a member rotatably supported on said body and having a bottom seating surface adapted to seat on said top seating surface of said body, said bottom seating surface being provided with a groove whose width and depth increases progressively from one end and a slot-like continuation at the other end of said groove, both said groove and said slot-like continuation being concentric with respect to the axis of rotation of said member, and being movable over said orifice upon rotation of said member for controlling venting from said orifice at a geometric rate.

7. In a device of the character described, a casing having an inlet, means to permit discharge of air from said casing, said means comprising a body supported in an opening in said casing and having an outlet orifice provided with a valve seat at one end and a top seating surface at its

other end, a temperature-operated valve within said casing cooperating with said seat, a member rotatably supported on said body and having a reentrant portion provided with a bottom seating surface adapted to seat on said top seating surface of said body, said bottom seating surface being provided with a groove whose width and depth increase progressively from one end, and a slot-like continuation at the other end of said groove also progressively increasing in width, both said groove and slot-like continuation being concentric with respect to the axis of rotation of said member and movable over said top seating surface upon rotation of said member, said member having a second portion defining a silencing chamber and a passageway connecting said two portions of said member, a locking member adapted to fit within said reentrant portion, said locking member having a reentrant chamber overlying said passageway and said groove and slot-like continuation and serving as a conduit for air vented through said orifice to said passageway, said two members operating in conjunction with said body for silencing and for controlling venting from said orifice at a geometric rate.

8. In a device of the character described, a casing having an inlet, means to permit discharge of air from said casing, said means comprising a body supported in an opening in said casing and having an outlet orifice provided with a valve seat at one end and a top seating surface at its opposite end, a temperature-operated valve within said casing co-operating with said valve seat, a modulator member rotatably supported on said body, a portion of said modulator member defining a sound deadening chamber with said casing, said modulator having a portion rotatable over said orifice, and said last-named portion having a bottom seating surface movable over said top seating surface and provided with a combination groove and slot extension thereof both concentric with respect to the axis of rotation of said modulator and which increase in width from a narrowest end of said groove at a geometric rate to a widest portion at the end of said slot furthest from said groove, and both movable over said orifice upon rotation of said modulator to control venting from said orifice at a geometric rate, and means in conjunction with said modulator for leading vented air to said chamber, said first-named portion of said modulator being arranged with respect to said casing to permit discharge of vented air from said chamber.

9. In a device of the character described, a casing having an inlet, a body supported by said casing and having an outlet orifice provided with a valve seat at one end and a top seating surface at its opposite end, a valve within said casing cooperating with said seat, a modulator member supported on said body, a portion of said modulator defining a sound deadening chamber with said casing, said modulator member having a portion rotatable over said orifice, and said last-named portion having a bottom seating surface movable over said top seating surface and provided with a combination groove and slot extension thereof both concentric with respect to the axis of rotation of said modulator and which increase in width from a narrowest end of said groove at a geometric rate to a widest portion at the end of said slot furthest from said groove, and both movable over said orifice upon rotation of said modulator to control venting from said

orifice at a geometric rate, means defining another sound deadening chamber into which venting air from said casing discharges prior to its entry into said first-named sound deadening chamber and means for directing the venting air from said second-named chamber into said first-named chamber.

10. In a device as per claim 6 in which said body has a sharp-edged annular dripping skirt arranged about said outlet orifice at a substantial distance therefrom.

11. In a device of the character described, a casing having an inlet and an outlet orifice, said outlet orifice being provided with an internal valve seat at one end and a top seating surface at its opposite end, a valve within said casing cooperating with said seat, and modulator means cooperating with said casing comprising means movable over said outlet orifice and adapted to vary the size of opening through the outlet orifice to control venting through said orifice at a geometric rate, said last-named means comprising a portion of said modulator having a bottom seating surface movable over said top seating surface, said bottom seating surface having a combination groove and slot extension thereof both movable over said orifice and which increase in width from a narrowest end of said groove at a geometric rate to a widest portion at the end of said slot furthest from said groove.

12. In a device of the character described, a casing having a pair of opposed faces defining a float chamber and joining curved faces connecting said pair of opposed faces and defining oppositely located auxiliary wing chambers each of which is in open communication with said float chamber, one of said opposed faces having an air inlet adjacent its bottom leading to the float chamber, a guide member arranged within said float chamber opposite said inlet and provided with a substantially vertical passageway opening into oppositely directed horizontal passageways above the normal liquid level in said device for guiding air and entrained droplets

of moisture entering said inlet first to above the said normal liquid level and then laterally in oppositely directed streams into said wing chambers and from there by the shape of said curved joining faces with a whirling motion into said float chamber, said float chamber having an air outlet in its top for the venting of air from it whereby the air is directed against the curved faces of said wing chambers, the latter forcing it to turn sharply prior to its discharge, said wing chambers being so admeasured that entrained water bubbles are able to expand in an enlarged space beyond their point of discharge into said wing chambers and their water membranes forced to stretch and burst before they can reach said outlet, and means for silencing the air venting through said outlet.

13. In a device of the character described, a casing having a flat face, a curved face opposite said flat face and curved joining faces connecting said two first-named faces, said curved joining faces defining oppositely-located wing chambers and said two first-named faces defining a float chamber in open communication with both said wing chambers, said flat face having an inlet, a guide member arranged internally of said float chamber opposite said inlet and provided with a substantially vertical passageway opening into two oppositely-directed horizontal passageways above the normal liquid level in said device whereby air and entrained droplets of moisture entering said inlet will first be directed vertically to above the said normal liquid level and then transversely in oppositely-directed separate streams toward and into the said wing chambers and from there by the shape of said curved joining faces with a whirling motion into said float chamber, said float chamber having an outlet in its top for the escape of air from it whereby the horizontal component of air velocity above the normal liquid level in said device will exceed the vertical component of said velocity in the passage of said air through said device.

WALNWRIGET TUTTLE

CERTIFICATE OF CORRECTION.

Patent No. 2,334,047.

November 9, 1943.

WAINWRIGHT TUTTLE.

It is hereby certified that error appears in the printed specification of the above numbered patent requiring correction as follows: Page 3, first column, line 57, for "and at II" read --and at III--; and that the said Letters Patent should be read with this correction therein that the same may conform to the record of the case in the Patent Office.

Signed and sealed this 11th day of January, A. D. 1944.

Henry Van Arsdale,
Acting Commissioner of Patents.
